ATTORNEY.

UNITED STATES PATENT OFFICE.

CHARLES G. MILBEANDT, OF DULUTH, MINNESOTA.

DEVICE FOR OPENING AND CLOSING DOORS OF BUILDINGS.

1,255,770.

Specification of Letters Patent.

Patented Feb. 5, 1918.

Application filed March 12, 1917. Serial No. 154,085.

To all whom it may concern:

Be it known that I, CHARLES G. MILBEANDT, a subject of Great Britain, residing at Duluth, in the county of St. Louis and 5 State of Minnesota, have invented a certain new and useful Device for Opening and Closing Doors of Buildings, of which the following is a specification.

The object of my invention is to provide 10 a simple and inexpensive mechanical means of opening, and closing doors of buildings, such as garages, car barns, stores and the like, by the application of motor power or hand power, as desired; and in a case where 15 the device is attached to a garage and operated by motor power, my object is to provide means by which the doors may be opened and closed without the necessity of alighting from the automobile or vehicle in 20 which one may be riding.

I accomplish these objects by means of the device shown by the accompanying drawings in which—

Figure 1, is a top view of said device when 25 attached to a building having double doors, the doors being open, and the dotted lines showing one door partially closed and the other one entirely closed. Fig. 2, is a view of said device as it appears from the inside 30 of the building, the doors being partially closed. Figs. 3 and 4, are side and front views respectively of a gear-box attached to the frame of the door and of the parts immediately connected therewith. Figs. 5 and 35 6, are side and front views respectively of the main gear of said device, and Figs. 7 to 12, are enlarged detailed views of different parts of said device hereinafter more fully explained.

40 Referring to Figs. 1 and 2, the doors 1, swinging on the hinges 2, are pushed open or drawn closed by the racks 3, pivotally connected to the bars or upper parts of said doors; and horizontal endwise motion is im- 45 parted to said racks 3, from the driving shaft 4, supported by the main gear-box 5, and the auxiliary gear-boxes 6, and which has fixed thereon the pinions 7, positioned within said gear-boxes 6, that is, between 50 the sides thereof, and adapted to mesh with the cogs 8, (Figs. 3 and 9) on the under side of said racks 3, said shaft 4, being caused to revolve by means of the gear-wheel or pinion 9, fixed thereon, which meshes with 55 the gear-wheel 10, rigidly and co-axially secured to the side of the larger gear-wheel

11, by means of the screws 12 (see Fig. 5), and this larger gear-wheel 11, may be turned by any suitable or convenient power such as by the electric motor 13, secured to the wall 60 of the building, preferably on the inside, and near the main gear-box 5, by means of the screws or nails 14, and from which extends the shaft 15, having the pinion 16, which meshes with said gear-wheel 11. The 65 gear-boxes 6, are attached to the inside upper part of the door-frame by means of the screws 17, and are preferably attached to the casing 18, and the jamb 19, as shown in Fig. 3, and so as to extend obliquely downward 70 and toward the inside of the building. The main gear-box 5, is likewise fastened to the wall near one of the upper corners of the door-opening by means of the screws 20. The shaft 4, extends through a hole in one 75 side 21, of said main gear-box 5, and through the holes 22, (Fig. 3) in the sides of said gear-boxes 6. In cases where the doors swing inward, the gear-boxes and shaft may be placed on the opposite side. In some 80 cases it might be desirable to use only ordinary bearings or brackets for supporting the shaft 4, from the wall or door-frame, instead of regular gear-boxes.

The pinions 7 and 9, may be secured to 85 said shaft in any customary and convenient way such as by a set-screw 23, threaded radially in said wheel and into a longitudinal groove 24, in said shaft, (see Figs. 10 and 11) which groove may be made to extend 90 the whole length of said shaft if desired, so that said pinions may be taken off said shaft, or shifted longitudinally thereof and still be made rigid at any desired point, by means of said set-screw 23.

95 The wheels in the gear-box 5, may be provided with the collars or lugs 25, on one or both sides (see Fig. 6) to reduce friction and prevent lateral movement, and the wheels 9 and 10, may be made of unequal 100 size and both be provided with the holes 26, so that they may be reversed in position with reference to each other and the speed of the shaft 4, thereby regulated; and, of course, all the different wheels will be made 105 of such size as to secure the desired slowness of speed in the revolution of the shaft 4, and correspondingly slow opening and closing of the doors, the large wheel 11, especially, being intended to greatly reduce 110 the said speed by working in connection with the small pinion 16, as well as to cor-

respondingly increase the power of the motor.

The racks 3, are pivotally connected to the angle-irons 27, rigidly attached to the doors 5 by means of screws 28, (see Fig. 7). The pivots 29, on said angle-irons 27, are preferably made with reduced diameters at their upper ends and threaded, so that a washer 30, may be placed upon the shoulder thus 10 formed and a nut 31, screwed down upon said washer, to avoid undue pressure on the racks 3. Fig. 8, is a top view of the connection of said arm to the door, a side view of which is shown in Fig. 7.

15 The racks 3, are curved so as to enable them to move in said gear-boxes approximately at right angles to the shaft 4, and operate horizontally on the plane of their curves, and are provided with cogs 8, between the flanges 32, on the under side (see 20 Figs. 3 and 9) and these cogs extend transversely of said racks but parallel with the plane of their curves and are adapted to work between the cogs 33, of the pinions 7, 25 in the gear-boxes 6, and said racks and cogs operate on the upper edge of each of said pinions and through said gear-boxes 6, being held down upon said pinions 7, by means 30 of the rollers 34, (see Fig. 4 where a rack 3 is shown in cross section). Revolving movement of said shaft 4, will cause said pinions 7, to turn in the boxes 6, and these pinions meshing with the cogs on said racks 3, will draw said racks and the doors attached thereto, inward for closing said doors, and with the reverse movement of 35 said motor and shaft will push said racks and doors outward for opening said doors. Said motor may be started or stopped by 40 the use of a key or other suitable means in connection with a switch box or station. One switch box may be placed inside of the building and one outside, if desired, at convenient distances from the wall. As I do 45 not claim the use of said motor and switch boxes as new the wiring to or between the same is not shown by the drawings.

Since the distance between the hinges 2, and the line of the shaft 4, may vary with 50 the different buildings, I may, if desired, have the racks 3, provided with the extension-pieces 36, shown in Fig. 12, so as to allow of said arms being extended or shortened as may become necessary.

55 In order to provide an automatic stop of the motor when the doors have been swung entirely open, one of said racks 3, may be provided at its inner end with a downward projection 36, (see Fig. 3) through which 60 extends the bolt 37, slidable in a hole therein, but held in extended position by the spring 38. An electric button 39, is positioned on the gear-box 6, and may be connected by wires to an ordinary three-way 65 electric switch. As the door swings open

the bolt 37, will push said button inward and cut off the electric current so as to stop the motor, and said spring 38, will prevent any sudden jar. Likewise when the door is entirely closed the electric button 40, on the 70 jamb 19, of the door will engage the head of the bolt 41, screwed in the door 1, as shown in Fig. 3, and cut off the electric current. However, as I do not claim these features as new the wiring to the switches 39 75 and 41, is not shown by the drawings.

Of course my device may be used for a single door as well as for a plurality of doors, in which case only one rack and one auxiliary gear-box would be required. 80

What I claim is:

1. In a door opening and door closing device the combination of a horizontally swinging door, a horizontally curved rack bar pivotally connected to the upper portion 85 of said door and having cogs lying in a horizontal plane parallel with the plane in which said rack bar lies, a shaft journaled in bearings fixed above the opening for said door, and a pinion fixed on said shaft to engage said rack bar.

2. In a door opening and door closing device the combination of a horizontally swinging door, a horizontally curved rack bar pivotally connected to the upper portion 95 of said door and having cogs lying in a horizontal plane parallel with the plane in which said rack bar lies, a shaft journaled in bearings fixed above the opening for said door, a pinion fixed on said shaft to engage 100 said rack bar and means for holding said rack bar in operative position on said pinion.

3. In a door opening and door closing device the combination of a horizontally 105 swinging door, a horizontally curved rack bar pivotally connected to the upper portion of said door and having cogs lying in a horizontal plane parallel with the plane in which said rack bar lies, a shaft journaled in bearings fixed above the opening for said door, a pinion fixed on said shaft to engage said rack bar, means for holding said rack bar in operative position on said pinion, and means for revolving said shaft in said 110 bearings.

4. In a door opening and door closing device the combination of a horizontally swinging door, a horizontally curved rack bar pivotally connected to the upper portion 120 of said door and having cogs lying in a horizontal plane parallel with the plane in which said rack bar lies, a shaft journaled in a gear-box fixed above the opening for said door, a pinion fixed on said shaft, in said 125 gear-box, to engage said rack bar, and means for holding said rack bar in operative position on said pinion.

5. In a door opening and door closing device the combination of a plurality of 130

- horizontally swinging doors, a plurality of horizontally curved rack bars pivotally connected to the upper portions of said doors and having cogs lying in horizontal planes 5 parallel with the planes in which said rack bars lie, a shaft journaled in bearings fixed above the opening for said doors, and pinions fixed on said shaft to engage said rack bars.
- 10 6. In a door opening and door closing device the combination of a plurality of horizontally swinging doors, horizontally curved rack bars pivotally connected to the upper portions of said doors and having cogs lying 15 in horizontal planes parallel with the planes in which said rack bars lie, a shaft journaled in gear-boxes fixed above the opening for said doors, pinions fixed on said shaft, in said gear-boxes, to engage said rack bars, means for holding said rack bars in operative position on said pinions, and means for revolving said shaft in said gear-boxes.
7. In a door opening and door closing device the combination of a plurality of horizontally swinging doors, horizontally curved rack bars pivotally connected to the upper 20 portions of said doors and having cogs lying in horizontal planes parallel with the planes in which said rack bars lie, a shaft journaled in gear-boxes fixed above the opening for said doors, pinions fixed on said shaft, in 25 said gear-boxes, to engage said rack bars, means for holding said rack bars in operative position on said pinions, and means for revolving said shaft in said gear-boxes.

CHARLES G. MILBRANDT.
